UNITED STATES PATENT OFFICE.

BENJAMIN F. HENKLE, OF WOODENSBURG, MARYLAND.

INKSTAND.

SPECIFICATION forming part of Letters Patent No. 397,983, dated February 19, 1889.

Application filed September 5, 1887. Renewed October 11, 1888. Serial No. 287,857. (No model.)

To all whom it may concern:

Be it known that I, BENJAMIN F. HENKLE, a citizen of the United States, residing at Woodensburg, in the county of Baltimore and State 5 of Maryland, have invented certain new and useful Improvements in Inkstands; and I do declare the following to be a full, clear, and exact description of the invention, such as will enable others skilled in the art to which 10 it appertains to make and use the same.

My invention relates to that class of inkstands in which the depth of dip of the pen is regulated by an adjustable gage-plate adapted to be placed in the body of the ink and the de- 15 sired distance below its surface.

It is the object of my invention to provide adjusting devices for such a plate which will constantly maintain, no matter what may be the vertical position of the plate, a fixed relation 20 to the inkstand.

By my invention I insure that there shall be no projections of varying distance above the top of the stand according to the height of the plate, and thus produce an article neat and 25 uniform in appearance and one not liable to be overturned by objects striking or catching upon such projections. Moreover, where the plate-adjusting devices surround the dip-opening 30 of the inkstand, I am enabled to apply a hinged cover of the ordinary character, which could not be done if the adjustment of the plate involved a change of distance of such adjusting devices above the top of the ink- stand.

35 My invention comprises, essentially, a nut carried by a gage-plate and a vertical screw-threaded shaft or shafts engaging with said nut and secured to the cover of the stand in such manner as to be capable of rotary or in- 40 capable of vertical movement.

My invention further comprises certain de- tails of construction hereinafter particularly described and set forth.

In order to enable my invention to be clearly 45 understood, I have shown in the accompanying drawings means for carrying the same into effect.

In said drawings, Figure 1 is a vertical sec- 50 tion of an inkstand embodying my invention. Fig. 2 is a horizontal section on line 2-2, Fig. 1. Fig. 3 is a top view of the gage-plate and a portion of its adjusting devices. Figs. 4, 5,

and 6 are vertical sections illustrating other forms of inkstand also embodying my invention.

Referring to the drawings, A indicates the body of my inkstand, which is made, preferably, of glass, but which may be of any other suitable material. It is provided with notches or recesses *a* around its upper edge. In these 60 recesses fit headed bolts *b*, which pass up through holes in the top B and are provided at their upper ends with nuts *b'*, adapted to be forced down upon the top and clamp the latter securely and rigidly to the body A. 65

The cover C is preferably hinged, the support for its pivot *c* being furnished by a bracket, *b*², carried by the top B. The hinge may, however, be dispensed with and an entirely removable cover may be employed. 70

D indicates the adjustable gage-plate, situated within the body of the stand beneath the dip-opening B', and preferably extending entirely across the ink-reservoir, as shown, its periphery being in close proximity to the 75 walls of the reservoir. The plate is provided with a number of notches or perforations, *d*, for the passage of the ink.

E is a nut or nuts carried by the plate D and made rigid with or secured from rotation 80 in the same.

F indicates a screw or screws mounted in a stationary portion of the inkstand, so as to be capable of rotation, but held from endwise movement. This bearing may be furnished 85 by the top B, as indicated in Figs. 5 and 6, or by an auxiliary plate, B², as seen in Figs. 1, 2, and 4.

Screws F engage the nuts E by their threads, and it will thus be seen that when they are 90 rotated a vertical movement of the plate D results, said plate being carried by the nuts. This rotation of the longitudinally-stationary screws F may be effected in various ways appropriate to my invention. By preference I 95 provide the screw or screws with gear-wheels G, which mesh with and are adapted to be rotated by a toothed sleeve, H. The latter surrounds the dip-opening of the top B and has its bearing therein. As seen in Figs. 1 and 4, 100 said sleeve has a peripheral flange, *h*, which fits against the under surface of the top. Above said top it is provided with a detachable annulus, I, which may be clamped to the

sleeve by a set-screw, *i*, or other suitable device. The annulus *I* may be milled, so as to be easily held and rotated by the thumb and finger. When such rotation is given to it, it will be seen, without further explanation, that by the corresponding rotation of the toothed sleeve *H*, engaging the wheel or wheels *G*, the screws *F* are revolved, thus effecting the vertical adjustment of the plate *D*, as already described, up or down, according to the direction of rotation of the annulus *I*. Said annulus and its toothed sleeve may, however, be dispensed with and the longitudinally-stationary screw *F* continued through and above the top *B* and provided with a peripheral flange, *f*, fitting against the under side of the top, and with a removable handle, *J*, which correspondingly and oppositely fits the upper surface of said top. The nuts *E* being the only parts besides the plate *D* which have vertical movement, and these being contained within the body of the inkstand, it will be seen that there will be no projection of varying height above the top of the inkstand to interfere with the operation of the cover or give opportunity for being struck or caught, with the risk of spilling the ink; but, on the contrary, the outside of the article always presents a uniform, neat, and finished appearance.

The nuts *E* are made to project below the lower face of the plate *D*, in order to furnish stops which will arrest the downward movement of the plate before it reaches the bottom of the reservoir. I thus insure that the ink above the plate into which the pen is dipped shall be free from sediment.

In order to prevent any binding between the screws and nuts and between the gage-plate and the walls of the reservoir, the nuts may be made separate from the gage-plate and fitted thereto by a tongue-and-groove connection, as shown in Figs. 1 and 3. This freedom of movement of the plate and nut relative to each other obviates the necessity for the accurate workmanship in the fitting of the parts which would otherwise be required, especially when two screws are employed, as shown in Fig. 1. The nut and plate may, however, be formed in one piece or rigidly secured together, as shown in Fig. 4.

I prefer to make the gage-plate, screws, and nuts of non-corrosive material, such as wood, hard rubber, or celluloid.

It is of course necessary that the gage-plate should be held so that while it can move vertically it shall not be able to rotate. Where two screws are used, as in Fig. 1, no other means are necessary for this purpose of preventing said rotation. In constructions like Fig. 4, also, (and the same is true of Fig. 6,) nothing is needed to prevent this rotation beyond the parts already described, the gage-plate being approximately of the same size as the cross-section of the reservoir, and the screw which engages it being eccentrically situated. Where a single screw concentrically situated is used, however, in a round

inkstand, some additional holding device is necessary. A very convenient means consists in providing the gage-plate with a projection 70 or a notch, and the inkstand correspondingly with a groove or a rib. The latter construction is illustrated in Fig. 5.

I am aware of Patent No. 369,101, in which a compressing-plate is situated beneath an 75 elastic reservoir, and I do not wish my claims to be understood as extending to such construction.

Having thus described my invention, what I claim, and desire to secure by Letters Patent 80 of the United States, is—

1. In an inkstand, the combination, with the reservoir and top having a dip-opening, of a gage-plate situated beneath the opening and within the ink-reservoir proper above its 85 bottom and held from rotation, a nut carrying said plate, a screw-shaft engaging the nut by its thread, and having a bearing in a portion of the stand in which the shaft rotates and is held from vertical movement, and an 90 external thumb-nut or handle for rotating the shaft, whereby the plate may be adjusted vertically within the body of the fluid, substantially as set forth.

2. The combination, with the reservoir and 95 top having a dip-opening, of a gage-plate situated within the reservoir and beneath the opening and held from rotation, a nut carrying said plate, a screw-shaft engaging the nut by its thread, and having a bearing in a portion 100 of the stand in which the shaft rotates and is held from vertical movement, a gear-wheel carried by the shaft, and a toothed sleeve surrounding the dip-opening and engaging said wheel, the outer end of the sleeve 105 being adapted to be turned to actuate and adjust the gage-plate, substantially as described.

3. The combination, with the reservoir and 110 top having a dip-opening, of a gage-plate 110 within the reservoir and beneath the opening, a plurality of nuts carrying said plate, corresponding screw-shafts engaging said nuts by their threads, and having bearings in 115 a portion of the stand in which they may revolve but are held from vertical movement, gear-wheels carried by the shafts, and a toothed sleeve situated in the opening and engaging said wheels, substantially as set 120 forth.

4. The combination, in an inkstand, with the reservoir, of a vertically-adjustable gage-plate situated beneath the dip-opening and having one or more nuts secured therein, and forming also projections upon its under surface, whereby it is arrested at a predetermined distance above the bottom of the reservoir, substantially as set forth.

In testimony whereof I affix my signature in the presence of two witnesses.

BENJAMIN F. HENKLE.
